SMOKING PIPE

William R. Patterson, Lomita, Calif.

Application October 8, 1948, Serial No. 53,428

4 Claims. (Cl. 131—213)

1

My invention relates to the field of smoking pipes, and more particularly to a pipe having a device positioned in the bore thereof whereby ashes, flakes of tobacco and moisture are prevented from being drawn into the mouth of the smoker.

Although numerous filters and traps for use in smoking pipes have been devised and marketed in the past, the majority of these devices have the disadvantage of a complicated mechanical structure which makes it difficult to maintain them in a clean and sanitary condition whereby they can satisfactorily perform the function for which they are intended.

It is a major object of my invention to provide a combination moisture trap and smoke filtering device that can be adapted to any one of the conventionally shaped smoking pipes, will have an extremely simple mechanical structure, can easily be removed from the pipe for cleaning purposes when the occasion so requires, is adapted to be fabricated from inexpensive material, and can be incorporated in a pipe at the time of its manufacture at a relatively small additional cost.

Another object of my invention is to provide a device which when removed from the bore portion of the pipe will at the same time automatically clean the bore due to this removal operation, with the device when so removed being easily separated into its component parts whereby each of these parts can be thoroughly cleaned with a minimum of effort.

These and other objects and advantages of my invention will become apparent from the following description when taken in conjunction with the appended drawings, wherein:

Figure 1 is a vertical longitudinal cross-sectional view of a straight stemmed pipe with my invention installed in the bore thereof;

Figure 2 is a perspective view of my combined moisture trap and smoke filtering device;

Figure 3 is a bottom plan view of the forward portion of the device;

Figure 4 is a vertical cross-sectional view of the device taken on the line 4—4 of Figure 1;

Figure 5 is a vertical cross-sectional view of the device positioned in a pipe having a slightly sloping stem;

Figure 6 is a vertical cross-sectional view of an alternate form of the device positioned in a pipe having an angularly positioned stem;

Figure 7 is a bottom perspective view of the alternate form of the device;

Figure 8 is a top perspective view of the alternate form of the device shown in Figure 7; and,

2

Figure 9 is an enlarged fragmentary vertical cross-sectional view of the front portion of the alternate form of the device shown in Figures 6, 7 and 8.

Referring to Figures 1 to 4 inclusive for the general arrangement of my invention, it will be seen that a conventional smoking pipe P is formed with a bowl 10, and a shank portion 11 extending outwardly from the rearward portion thereof. The shank 11 is provided on its outer end with a bit 12. Formed in the bowl portion 10 is a downwardly extending cylindrical cavity 13 in which the tobacco to be smoked is positioned, and from the downward portion of the cavity a small diameter bore 14 extends rearwardly. An annular shoulder 15 is formed at the junction of the bore 14 with a rearwardly and longitudinally extending bore 16 which has a considerably greater cross-sectional diameter than the bore 14. Extending outwardly from each side of the bore 16 is a longitudinally extending slot 17 as can best be seen in Figure 4 that terminates a short distance from the shoulder 15 for reasons which will hereinafter be explained. Slidably supported in the slot 17 within the confines of the bore 16 is a member 18 formed with a longitudinally extending flange 19 on each side thereof, and having a downwardly extending groove portion 20 of semi-circular cross-section which is of greater length than the flanges 19 whereby it protrudes rearwardly from the rear end of these flanges and defines when taken with the walls of the bore and the bit smoke apertures 21, the purpose of which will be hereinafter set forth. Situated in the groove portion 20 is a tubular member 22 that extends outwardly from the rearward end of said groove portion, and is provided on the forward end with an annular plate 23 having a number of horizontal bores 24 formed in the upper portion thereof. A transversely positioned slit-like opening 26 is formed in the forward part of the groove portion 20 as can best be seen in Figure 3, and is in vertical alignment with a similar opening 27 formed in the lower portion of the tubular member 22 (Figure 1). On the forward face of the member 23 is a circular centrally disposed forwardly curved member 28 that is adapted to be seated against the shoulder 15, and is provided with a slot 29 therein which serves as a passage to permit smoke to be drawn rearwardly from the bowl 10 through the bore 14. The assembly of the pipe P with my invention installed therein is extremely simple, with my combination moisture trap and strainer, as shown in Figure 2, being

inserted into the bore 16 until the member 28 is in contact with the shoulder 15 as shown in Figure 1. When thus assembled the flanges 19 occupy all but a small rearward portion of the slots 17, and the rear of the groove portion 20 is flush with the rearward edge of the shank 11. The rearwardly extending tubular member 22 is slipped into the forward end of the bore 30 formed in the bit 12 as a connection whereby tobacco smoke from the bowl 10 can pass to the smoker's mouth.

As smoke is drawn rearwardly from the cavity 13 it passes through the bore 14 to the member 28 which would normally block the exit from bore 14 were it not for a horizontal slot 29 provided therein. Upon reaching this point the smoke passes through slot 29 and is further blocked from moving rearwardly by the annular plate 23, with the only passage therethrough being the bores 24 formed in the upper portion of the plate above the flanges 19. The upper portion of the shank bore 16 is separated from the lower portion thereof by the flanges 19, with the exception of the smoke apertures 21 formed between the rearward edges of the flanges and the forward face of the bit 12. The smoke upon reaching the apertures 21 passes downwardly therethrough to reverse its flow in a forward direction until it reaches the transversely positioned slits 26 and 27 which permit it to move upwardly into the confines of the tube 22 whereupon it again reverses its direction to move rearwardly through the tube into the bore 30 of bit 12. It will be noted that the portion of the bore 16 below the flanges 19 is only in communication with the upper portion of the bore through the smoke apertures 21 as the plate 23 fits very snugly within the confines of bore 16. Thus it will be seen that in the operation of my invention ashes or flakes of tobacco are prevented from entering the bore 16, due to the plate 23 being firmly positioned against the side walls of the bore, and only permitting tobacco smoke to pass rearwardly through the bores 24.

Although moisture may be precipitated upon the flanges 19 and tube 22, it is difficult for this liquid to be drawn into the smoker's mouth through the bore 30 as the liquid will flow rearwardly along the upper surface of the flanges 19 to the apertures 21, and downwardly therethrough to the lower portion of the bore 16. However, even when the moisture or liquid is situated in the lower portion of the bore 16 it will not be readily drawn into the smoker's mouth as it cannot easily rise upwardly through the openings 26 and 27 to pass into the tubular member 22.

Such moisture as is precipitated in the bore 16 will be removed therefrom as my invention is removed from the stem 11 of the pipe for cleaning purposes by the plate 23 scraping both solid and liquid material from the face of the bore 16 as the tube 22 is moved rearwardly. With my invention removed from the confines of the bore 16 it is separated into two component parts 18 and 22, which due to their extreme mechanical simplicity are easily cleaned, and the parts then re-assembled to be placed into the pipe P as previously described to serve as a combined moisture trap and filter during the smoking of tobacco in the cavity 13.

In the pipe P' shown in Figure 5, my invention when incorporated therein is fabricated in substantially the same manner as the device used in connection with the pipe P. In the use of my

invention with the pipe P' I have found it convenient to form a downwardly and rearwardly extending bore 49 from the cavity 13' to the bore 16'.

5 The operation of my invention in either of the previously described pipes is extremely simple. After tobacco has been placed in the cavity 13 and lit, the smoke therefrom is drawn rearwardly to the smoker's mouth, passing through the bore leading to the forwardly disposed member 28 and thence upwardly to pass through the bores 24 into the upper portion of the bore 16. The smoke then moves rearwardly to the apertures 21 to reverse its flow in the lower portion of the bore 16 and upon reaching the forward portion thereof moves upwardly through the openings 26 and 27 into the tube 22. Upon the smoke entering the tube 22, it is pulled rearwardly therethrough to enter the bore 30 and thence into the smoker's mouth.

10 The alternate form of my device 50, as shown in Figures 6 through 9, is fabricated as an integral unit from an inert material, such as one of the synthetic plastics adapted for this purpose, which will not alter the taste of tobacco smoke passing through the device. The operation of the alternate form of my device 50 when installed in a pipe is substantially the same as my previously described form.

15 30 In referring to these figures, it will be noted that the alternate form of the device includes a tube 51 having longitudinally extending flanges 52 formed on each side thereof, with the flanges terminating a short distance from the rearward end 52a of the tube. Situated on the forward end of the tube 51 is a resilient annular packing 53 which engages the interior surface of the pipe stem bore in which the device 50 is positioned. The packing 53 is held in position between two 20 longitudinally spaced annular members 54 that are formed as an integral part of the tube 51.

25 In Figures 7, 8 and 9, it will be noted that two bores 55 extend rearwardly from the face of the device to terminate directly behind the rearwardly positioned annular member 54. Thus, as 30 tobacco smoke is drawn from the pipe bowl through the bores 55 it flows rearwardly above the upper surface 56 of the flanges 52 to pass downwardly through vertical bores 57 formed in the rearward portion of the flanges. The smoke then reverses its flow to move forwardly along the underside 58 of the flanges to pass upwardly through a bore or opening 59 into the tube 51. The smoke then reverses its flow to pass rearwardly through the tube 51 into the bit of the pipe as previously explained. The rearwardly extending portion 52a of tube 51 engages the forward end of the bit, and serves to removably hold the stem and bit of the pipe together.

35 40 45 It will be apparent that various modifications and changes may be made with regard to the foregoing description without departing from the spirit of the invention or the scope of the following claims.

50 55 I claim:

1. A moisture removing device for use in the straight shank portion of a pipe which includes: a tube having an opening formed in the lower forward portion thereof; two longitudinally spaced members mounted on said tube and situated forwardly of said opening; a resilient annular packing situated between said members and said members having a smoke passage extending longitudinally through the upper half thereof; 50 and two oppositely disposed flanges affixed to said

tube and extending along a portion of the longitudinal length of said tube, and said flanges having smoke passage means formed in the rearward portion thereof.

2. A moisture removing device for use in a smoker's pipe having a straight outer shank portion which includes: an elongated tube that has a rearward end portion that may be removably engaged by the bit of a pipe, the lower portion of the wall of said tube being formed with a bore; two longitudinally spaced annular members formed on the forward end portion of said tube and disposed forwardly from said bore, with said members having a smoke passage extending longitudinally through the upper half portion thereof; a resilient ring disposed between said annular members; and two oppositely disposed flanges extending outwardly from said tube between the forward and rearward end portions thereof, said flanges having smoke passages formed in the rearward part thereof.

3. A moisture removing device for use in a conventional pipe having a bowl formed with a straight centrally bored shank extending outward from its rearward portion, and a bit provided on the rear end of said shank, said shank being formed with a pair of longitudinally extending slots along the bore thereof, comprising: a tube capable of being longitudinally positioned in the bore of said shank with its rearward portion being adapted to slidably engage said bit, said tube having an opening in a portion of the wall thereof; a pair of longitudinally spaced annular members formed on the forward end of said tube; a resilient packing positioned between said annular members, said packing forming a seal with the bore of said shank; a longitudinally extending smoke passage formed through the upper half of said annular members; and a pair of longitudinally extending flanges extending outwardly from the exterior of said tube, said flanges being adapted to slidably engage said slots, and said flanges having smoke apertures in their rearward portions whereby smoke when drawn from said bowl may pass through said smoke passage, smoke apertures, and said tube by means of said opening therein in order that moisture contained in said smoke may be condensed in the lower portion of the bore of said shank to be removed therefrom by rearward movement of said tube, said rearward movement causing said packing to wipe the wall of said bore.

4. A moisture removing device for use in a conventional pipe having a bowl formed with a

straight centrally bored shank extending outward from its rearward portion, and a bit provided on the rear end of said shank, said shank being formed with a pair of longitudinally extending slots along the bore thereof, comprising: an elongated tube that may be longitudinally positioned in the bore of said shank, said tube having an opening in a forward wall portion thereof; two oppositely disposed flanges extending outwardly from said tube between the forward and rearward end portions thereof, said flanges being capable of engaging said slots, and said flanges cooperating with said bore to define upper and lower longitudinally extending smoke passages; two longitudinally spaced annular members disposed on the forward end portion of said tube, said members having a plurality of bores extending rearwardly therethrough that terminate in the rearmost of said members above said flanges; and a resilient ring situated between said members, the periphery of which effects a moisture-tight seal with said bore to cause all smoke flowing through said shank bore to pass rearwardly through said bores in said members and said upper passage to openings formed in the rearward part of said flanges through which it flows downwardly to travel forwardly in said lower passage until it enters the opening situated in the forward part of said tube, with the smoke then flowing rearwardly through said tube to enter said bit, and moisture condensing from said smoke as it traverses said lower passage being removable therefrom by rearward movement of said tube to cause said annular member to wipe said shank bore clean of moisture and foreign material.

WILLIAM R. PATTERSON.
